KNITTING MACHINE

Vincent Lombardi, Garden City, N. Y., assignor
to Lombardi Knitting Machine Co., Inc., New
York, N. Y., a corporation of New York

Application February 4, 1939, Serial No. 254,580

44 Claims. (Cl. 66—42)

This invention relates to knitting machines and to correlated improvements and discoveries appertaining thereto.

An object of the invention is the provision of 5 an improved form of knitting machine adapted to produce a variety of the types of design fabrics and fabrics of a similar character.

A more specific object is the provision of an 10 improved form of circular knitting machine adapted to produce improved types of fabrics wherein auxiliary yarn is present only at one or more portions of the fabric.

A further object is the provision of improved 15 means for incorporating yarn into a fabric in such manner that the yarn extends back and forth and is caught into the fabric in one or more portions of both its forward and return extents.

Other objects of the invention will in part be 20 obvious and will in part appear hereinafter.

The invention accordingly comprises features 25 of construction, combination of elements, and arrangements of parts, and the correlated constructions, all as exemplified in the detailed disclosure hereinafter set forth, the scope of the application thereof being indicated in the claims.

For a fuller understanding of the nature and 30 objects of the invention reference should be had to the following detailed description taken in connection with the accompanying drawings, in which:

Figure 1 is a vertical sectional view of one form of machine embodying the invention, certain of the parts being shown in elevation;

Fig. 2 is an enlarged vertical sectional view of 35 the lower left-hand side of Fig. 1, the drum casing being shown in elevation;

Fig. 3 is a vertical sectional view of the lower portion of the machine;

Fig. 39 is a horizontal sectional view along the line 39—39 of Fig. 38.

In Patent No. 2,130,769, issued to me on September 30, 1938, there are disclosed certain types of knitting machines whereby design fabrics embodying stripes, squares, triangles, circles, or other design portions of yarn of one color or character may be economically embodied in a fabric the main portion of which is composed of yarn of another color or character, or whereby strips or pieces of fabric which are wholly or partially unconnected in a course-wise direction may be formed, or whereby various other novel types of fabric may be produced. By the use of certain of the general principles involved in such machines, design fabrics, fabrics with heavy portions, fabrics with elastic portions, and fabrics of a wide variety of other types may be formed in a simple and effective manner and without employment of undue quantity of design or other yarn whose use at only portions of a fabric or a machine is desired, this being of particular importance in situations wherein relatively expensive design yarn, an elastic yarn, or other such yarn is utilized. The mechanisms particularly exemplified in said patent, while very satisfactory for certain purposes, are subject to certain limitations. It has been found that by the employment of reciprocable yarn guides and suitable associated mechanism various of these limitations may be overcome and various desirable results secured. Among such results are the provision of a wide variety of design fabrics which are impossible or difficult to produce on previously known types of machines, the handling of types of yarns which would be difficult or impossible to handle by previous mechanism, and the facilitation of knitting operations and of the production of various types of fabrics; and it is with machines and mechanisms for achieving such results that the present invention is primarily concerned. In certain of its aspects, however, the invention is concerned with the provision of mechanism utilizable alike in machines having reciprocable yarn guides and in machines wherein yarn guides are relatively stationary with respect to the needle bed.

While the invention in certain of its more specific aspects is directed to the provision of improved types of circular knitting machines and is exemplified in connection with a circular knitting machine having a stationary needle cylinder, the invention in various of its broader aspects may be embodied in circular knitting machines of any well known type, including cylinder machines, dial machines, and cylinder-and-dial machines, and also, in certain instances, on flat knitting machines; and may also be embodied in machines wherein the needle bed is rotatable or otherwise movable and certain of the other parts stationary, or wherein the needle bed is stationary and wherein certain of the other parts revolve about or otherwise move along said bed.

The invention, moreover, while exemplified in connection with a latch-needle machine, is in many of its aspects, equally applicable to a spring-needle machine, or to a machine having other types of needles.

In the drawings, rotating parts are cross-hatched with the lines running from the lower left to the upper right, and the stationary parts are cross-hatched with the lines running from the upper left to the lower right.

The form of machine exemplified in Figs. 1 thru 22 comprises a needle bed which, in the present instance, is in the form of a stationary needle cylinder 5, having slots 6 therein. In each of these slots, in the present instance, there is disposed a latch needle 7, it being understood, however, that the invention, at least in the majority of its aspects, is equally applicable to spring needle machines. Secured to the needle cylinder 5 is a sinker bed 8 in the slots 9 on which are disposed a series of sinkers 10 which are of conventional form and which are operated by a rotating sinker ring 11. Disposed centrally above the machine is a rotary spider 12, carrying bobbins 13 from each of which yarn is supplied to a main-yarn feed 14, carried on an arm 15 which is removably secured to a member 15' dependently carried from the spider. The spider is supported thru the medium of a plurality of posts 16, carried on a rotating annulus 17, and connected with the spider by means of arms 18. The annulus 17 is driven by means of a gearing 19 meshing with an annular gear 20 on the annulus and driven from a shaft 21 driven from a suitable source of power (not shown). The annulus 17 carries a cam ring 22 whereon needle raising cams and needle lowering cams are secured. Some of the needles are formed with long butts 23, and the remaining needles with short butts 24, and suitable raising cams are provided in advance of the passage of the main-yarn feeds. In advance of some or all of the main-yarn feeds 14 (all in the present instance) needle raising cams 25 which raise all the needles to a latch clearing position are provided. In instances where knitting of loops at each main-yarn feed is not desired, cams which raise only the long butt needles to a partially-advanced yarn-receiving position in advance of the passage of certain of the main-yarn feeds may be provided. Needle retracting cams 27 serve to retract all advanced needles after the passage of the main-yarn feeds and at other points where needle retraction is desirable.

In the exemplified form, the machine is adapted for the knitting in jersey fashion of the main yarn from at least certain of the main-yarn feeds, with or without the incorporation of other main yarn in laying-in or interlock fashion at other of the main-yarn feeds, and for the incorporation of auxiliary yarn at only certain portions of the fabric in a laying-in or interlock manner without knitting. In order to supply this auxiliary yarn to the needles, there are provided a plurality of reciprocable yarn-guide portions 29 adapted to draw design or other auxiliary yarn back and forth across a limited number of needles. Each portion 29 forms a part of a yarn-guide member 30, which, in the present instance, is formed of flat spring-steel, and mounted in a manner hereinafter to be described on a ring 31 which is freely supported on a ring 32 carried by the posts 16. The ring 31 carries an annular gear 33 meshing with gears 34, affixed, respectively, to shafts 35 journaled in a casting 36 which is secured to the posts 16. Affixed to the lower end of each shaft 35 is a gear 37, meshing with an annular gear 38, carried on a stationary dial 39 which is secured to and supported by extensions 40 of the ridges between the slots 6. The ring 31, accordingly, while supported by a rotating annulus 32, is maintained stationary thru the medium of the duplicate gearing, the operation 75

of which is controlled from the stationary dial 39. The auxiliary yarn is supplied to the auxiliary-yarn feeds from bobbins 41 thru the medium of suitable conducting members including 5 a yarn retarder 42 and a yarn-tensioning means including an eyelet 43 carried on a spring 44.

Each of the auxiliary-yarn feeds is adapted to move back and forth across all or some of a limited group of needles. In the exemplified form 10 of construction, for the purpose of effectuating this back-and-forth movement, there is provided driving means actuated by a rotatable annulus 45, which is supported by a ledge 46 on the ring 31 and is driven by means including arms 47 15 connected with the spider 12 so as to rotate in unison therewith. In the present instance, all of the yarn-guide members 30 are mounted for operation from a single reciprocable ring 48 which is mounted for free movement on the ring 20 31. The reciprocable ring 48 has secured thereto at one or more points thereon a stud 50 which extends into a slot 51 in the arm 52 of a bell crank lever 53 which is pivoted at 54 to the ring 31. The other arm 55 of the bell crank lever 25 carries at a point inward of the lever a roller 56 which is disposed in the path of each of a plurality of cams 57 carried on the rotatable annulus 45. Each cam is so shaped that when it passes it will raise the roller 56 and will swing 30 the bell crank lever 53 on its pivot 54 to move the ring 48 to the left in Fig. 5, the slot 51 being of such shape that there will be no tendency to displace the ring 48 vertically. The shape of each cam 57 is such that it will hold the roller 35 raised, and ring 48 in its moved position, for a desired period and will then permit the roller to trip and the ring to be drawn back by a spring 58. There are provided on the ring 48 a plurality of plates 60, corresponding in number to 40 the number of yarn-guide members 30. Bridging each space between successive plates 60 is a spring unit comprising a spring 61 one end of which grips a stud 62 on one plate and the other end of which grips the throw 64 of a crank 65 mounted in the ring 31, and a similar spring 66 45 which grips a stud 67 on an adjacent plate and also the throw 64 of the crank 65. Each crank 65 carries at a point exteriorly of the ring 31 a crank pin 68 at the end of an arm 69, and on 50 this pin 68 is mounted the upper end of the yarn guide member 30, the lower end of which carries the yarn guide portion 29. Freely mounted on a pin 70, carried more or less centrally of the yarn-guiding member 30 is a link 71 fixed to the 55 shaft 72 journaled in the ring 31, and secured by a head 73. The pin 70 forms part of a screw 74 and the pin 70 forms part of a screw 75, the heads of these screws acting to prevent bending of the upper part of the spring steel yarn-guiding member 30. The maximum possible length 60 of a stroke of the yarn-guiding portion 29 will accordingly be determined by the length of the various links and crank arms involved. Preferably, and as exemplified, the length of the stroke 65 will be such that each movement of the yarn-guide 65 70 75 70 will be greater than the greatest extent of a design to be formed therefrom, so as to assure the proper feeding of the yarn to the needles raised, and to facilitate varying the width of patterns.

It is to be observed that the exemplified arrangement of the cranks is such that the tip of the yarn-guiding portion 29 will always move in a horizontal plane so that yarn will be fed to the 5 needles therefrom at the same level regardless

of the position in its stroke at which yarn-guiding member may be. In order that the strokes of the yarn-guiding portions 29 may conform to the arc of the group of needles past which it moves, there is provided on the stationary ring 5 31 in connection with each member 30, at a position spaced below the lowermost position of the pin 70, a cam 76 having an inclined surface adapted to bear against a detent 77 formed in the member 30 at a point spaced beneath the pin 70. 10 Since the member 30 is formed of spring steel, it will swing outwardly under influence of the cam 76. The shape of this surface is such that the arc of movement of the tip of the portion 29 will conform to the arc of the needle bed. The 15 vertical extent of the cam 76 is desirably sufficient to embrace the vertical movement of the detent 77, altho, of course, a cam exactly conforming to the path of movement of the detent 20 may be employed.

The mechanism such as above described will operate admirably for the formation of patterns of substantially uniform width, such as substantially vertical stripes, squares, and the like, and will also operate for the production of variable 25 width patterns. In the formation of patterns which vary considerably in width, however, there will be occasions when large amounts of yarn will have to be rapidly taken up from time to time by the yarn-tensioning means 43. This not only results in a considerable wear on the yarn, but also requires a tensioning means of such strength that an especially thin yarn may be broken thereby. Also, the provision of special instrumentalities is required to prevent yarn drawn out to one side 30 or other of the pattern from being caught by the sinkers. In order to avoid the foregoing and other difficulties, there are provided in accordance with the invention means to vary the actual stroke of the yarn-guiding portion 29 in accordance with the extent of the pattern at the particular point of activity of the yarn-guiding member at a given period of the operation; the stroke being, however, greater than the extent 40 of the pattern whether the extent of the stroke 45 is large or small. The particular means to this end exemplified comprises a spring steel control finger 80, mounted on the pin 70 and carrying a lug 81 guided in an arcuate slot 82 formed in the yarn-guiding member 30 above the pin 70, 50 the width of the lug being somewhat less than the extent of the slot, so that tendencies toward movement of the member 30 will tend to impart to the finger 80 movement which is similar in direction, but less in extent than the movement 55 of the member 30. The fingers 80 are formed on the lower ends with outward bends 83 in the path of which selected ones of a plurality of stops 84 are adapted to be disposed. These stops 84 form a part of members 85 slidably disposed in 60 slots 86 in the dial 39, and carrying at their ends resilient members 87 each having a compressible portion 88. The slideable members 85 are uniformly spaced about the machine, at least one member 85 being provided for each of a successive 65 number of needles in each group. In the present instance the number of members 85 is equal to the number of needles, but each member 85 is arranged to be operated by either of two needles as exemplified, or by any of a number of needles if desired, so that, even tho only spaced needles are raised, a suitably positioned stop member will still be actuated.

The members 85 are slideable between the inward position in which the stops 84 will be in 75

the path of movement of the bends 83 of the control members 80 and an outward position in which the stops 84 will be out of the path of such movement. As will be apparent, when the members 85 are all in an inward position, the control members are held against movement in either direction, whereas if certain of the stops adjacent a control member are in an outward position, the control member can move in at least one direction until it encounters a stop which is in an inward position. Accordingly whenever it is desired to limit the swing of the yarn-guiding members 30, it is only necessary to have suitable stops in an inward position. Due to the lost-motion arrangement at 81—82, the yarn-guiding members will never be held entirely against the movement, but will at all times be allowed to swing a limited distance under the influence of the pressure-springs 61 and 66. When a control member 20 80 is permitted to have a small movement, the amount of this movement will be added to the amount of movement which its yarn-guiding member will have when the control member is held against movement, and when a control member 25 85 is permitted to have a large movement, the amount of this movement will likewise be added to the amount of movement which its yarn-guiding member will have when the control member is held against movement. In advance of each 30 needle wave for the incorporation of yarn from the yarn guides 29 (which wave will be referred to as a "design wave"), and at a time when the ring 48 is stationary, a cam 90 carried by the rotating framework 36 moves all of the members 35 85 to the inward position, so that they may be selectively moved outwardly. In accordance with the present invention in certain of its aspects, this movement occurs while the needles are retracted and the needles thus may be utilized to selectively 40 effectuate outward movement of such stops as it is desired to be inoperative. To this end each needle is formed with an outwardly extending portion 91, having a cam surface 92 adapted to bear against a cooperating end portion 93 of the 45 resilient member 87. Each end portion 93, as above indicated, spans two needles, so that, if either or both of these needles are raised, the end portion 93 will be thrust to an outward position. The raising of either needle (or, if the end-portion 50 55 spans three or more needles, the raising of any one or more of these needles) may thus result in the removal of the stop. This facilitates the formation of designs wherein the design yarn is incorporated in the fabric without knitting as by a laying-in procedure, in which event alternate needle (or other spacings of needles) are partially raised to receive yarn without casting. By controlling the position of the stop members in accordance with the needle action, the movement 60 of the yarn guiding member in any particular instance is made dependent upon the particular needles raised, and the knitting of design formations, such as zigzags, diamonds, and the like, without the drawing out of excessive amounts of 65 yarn, is greatly facilitated, since stop members will be in place at all positions, except the positions where needles are actually raised to receive yarn for making a particular part of the design.

In Fig. 5 it is to be noted that yarn guiding members 30 shown are exemplified as having different amounts of swing in accordance with different settings of the stops which limit the movement of their respective control fingers 80. The yarn guide members illustrated in this figure are indicated at A, B, C, D, E, and F, and the extent

of movement of each of these yarn guide members, as well as the extent of any movement of each control finger associated therewith, when the reciprocal ring 48 is shifted to the left of Fig. 5 is indicated in dotted lines. The control finger 5 of the yarn guide A is held in a central position and the yarn guide A has only its lost-motion movement. The control finger of the yarn guide B is permitted a small movement by the particular setting of the stops, so that the yarn guide B 10 has a small movement. The control finger of the yarn guide C is permitted a large movement, and the yarn guide C will have a large movement in addition to its lost motion. The control member of the yarn guide D is held by the action of the 15 stops in a position fully to the left of Fig. 5, and yarn guide D will only have its lost motion but this will take place in a leftward position. It is to be noted that by its lost motion the yarn guide D is drawn out of the way of the yarn guide C as 20 the latter is moved to the right of Fig. 5, so that, even tho the guides are aligned—as, for example, in an outward position, as hereinafter explained, the guides will not contact each other. The yarn guide E has a large movement similar to the 25 movement of the yarn guide C; and the yarn guide F has a movement similar to that of the yarn guide B.

In order that the fingers 80 may be extended down to contact stop members operated by elements on the needle bed, it is necessary that special means be provided for rotating the sinker cam ring. To this end there is provided one or more gear trains each comprising a shaft 95 journaled to a bearing 96 mounted on a bracket 97, 30 which is supported on the dial 39. At the end of the shaft 95 are pinions 97' and 98 meshing, respectively, with annular gears on the framework 36 and the sinker-cam-ring 11. As will be seen in Fig. 4, those fingers 80 which are in juxtaposition with the bearing 96 are bent as at 100 and 101 so as not to be interrupted in their course by the bearing 96. Their bends 83 will, however, be in the same relative position as, and operate exactly similar to, the bends on those fingers 80 45 which are straight.

In order to selectively control the needles at the design portions, there may be provided any suitable form of selective mechanism. The form particularly exemplified is similar to the form 50 shown in Figs. 1-13 of my Patent 1,792,647, and for a detailed description of the same and of the operation thereof reference may be had to said patent.

As will be seen, there is provided in each of 55 the needle slots 6 at a point beneath the needles a jack 110 having a butt 111 adapted to be engaged by a cam 112 which, it is to be noted, is of less vertical extent than the cam 42 of my said Patent 1,792,647, since the latter cam is designed 60 to raise the needles to fully advanced position, whereas the cam 112 in the present case is designed to raise selective needles only to partially advanced position. The jacks 110 are, of course, frictionally set in the slots, and in advance of 65 each design wave, a cam 113 moves the jacks outwardly to the position in which their butts 111 will be engaged by the cam 112. Prior to the passage of the cam 112, however, all or some of these jacks may be thrust inwardly by selected 70 slid elements 114. The needles associated with the jacks which are pressed inwardly by the elements 114 will accordingly not be raised by the cam 112, whereas needles which are not moved inwardly by jacks will be selected by the 75

cam 112 and moved to partially advanced position. The selective operation of the slidable elements 114 for the control of the jacks 110 for each design wave is effected by one of a series of drums 115, carried by the rotating annulus 17. These drums are of the character exemplified in Figs. 1-13 of my said Patent 1,792,647 and the settings thereon are selectively effectuated thru mechanism, such as shown and described in my said Patent 1,792,647, from a pattern band 116 carried on a drum 117 as in Fig. 2 of my last-mentioned patent. An annulus 118 carrying the cams 113, and an annulus 119 carrying cams which form parts of the setting control member, are driven from a shaft 21, thru the medium of gear connections 120 and 121 respectively.

As above set forth, the yarn guide members 30 are formed of spring steel, and, as will be seen, the yarn guide portions 29 may readily be moved outwardly. In order to assure that no yarn guide portion 29 will be in position for reception of yarn therefrom by the needles or sinkers during a needle wave associated with the main-yarn feed, and to permit the main yarn feeds to pass the yarn guides, there is provided in connection with each main-yarn feed 14 in the present instance a deflector wire 121' carried by arm 15 and formed in the shape of a bow.

In order that the stops 84 will not be moved outwardly when needles are raised by the cam 25 for reception of yarn from the main yarn feeds, there is provided positive means to hold stops inwardly during the needle waves accompanying the main-yarn feeds. In the present instance, this means is carried on the rotating framework 36 and consists of rearward extensions 122 of the cams 90. The raising of needles by a cam 25 accordingly results merely in compression of the compressible portions 88 of the members 87 and not in the movement of the stops. The sinker ring 11 is formed with a cam groove 123 acting on butts 124 of the sinkers and adapted to move the sinkers out and in in the usual manner each time a needle wave may occur. In Fig. 21, cam portions causing outward and inward movements of the sinkers for the wave caused by the cams 25 and 27 are indicated at 125, and cam portions for causing outward and inward movements of the sinkers for the knitting wave caused by the cams 112 and 27 are indicated at 127. The outward and inward movements occur regardless of whether selective mechanism is set to raise needles at any particular point. In the formation of design fabrics there will, however, ordinarily be numerous points where designs are spaced walewise of one another, and, in order to prevent the yarn from a yarn guide from being caught by a sinker during the small back-and-forth movement permitted the yarn guide even when all the stops are in place, there are provided means to hold the yarn guide in an outward position wherein yarn will not be received therefrom by the sinkers at such times. It is often, moreover, desirable that during the formation of certain patterns other patterns be interrupted, as for example when one yarn guide carries yarn of one color, the next yarn guide carries yarn of another color, and the succeeding yarn guide carries yarn of still another color, and patterns of yarn of these different colors are spaced apart from one another in a relatively walewise direction. With considerations of such nature in view, each cam member 76 is, in the present

instance, mounted for outward and inward movement by means of a pin 130 extending inwardly from the cam member 76 and slidably mounted in a hole 131 in the ring 31, and pressed by its resilient member 30 against a control annulus 132 which is freely supported on the annulus 45. The outer surface of the annulus 132 is formed with recessed and protruding portions with cam surfaces therebetween so that small rotative movements of the annulus will bring either a recessed or a protruding portion opposite the inner end of a pin 130. When a recessed portion is opposite the inner end of a pin 130, the respective cam member 76 will be in an inward position and the member 30 and 15 yarn guide 29 associated therewith will be in position to be operated to feed yarn to such needles as may be raised for reception of yarn therefrom, but when a protruding portion has been brought into place against the inner end of 20 this pin, the cam member 76 will be thrust outwardly sufficiently to bring its respective yarn guide to a position so far out that not only can yarn not be fed to the needles thereby, but the yarn will extend outwardly between sinkers so 25 that it will not be caught by the sinkers and will remain in a given position vertically (walewise) of the fabric as long as the member 76 is thrust outwardly. When a protruding portion is aligned with a pin, the cam member 76 is 30 thrust outwardly so that the corresponding members 30 are held in an outward position such that its yarn guide will be held further out than the outermost position of the sinkers. In the particular form exemplified, the annulus 132 35 is constructed so that in the various ones of its positions any desired ones of a group of three yarn guides will be held outwardly at a given time. For example, in Figs. 13-20 there is indicated diagrammatically three cams 76a, 76b, 40 and 76c, and the annulus 132 is shown formed with protruding portions 133, 134, and 135, at a point in proximity to the cam 76a, with protruding portions 136, 137 and 138 at a point in proximity to the cam 76b, and with protruding portions 139 and 140 in proximity to the cam 76c. The portions 134, 136 and 139 have widened outer ends so that they serve in effect as two protruding portions. Accordingly, by small movement of the annulus 132 between the positions 45 shown in Figs. 13-20 various combinations of actions are possible as exemplified, so that the protruding portions will be so aligned with respect to the pins that all the cams 76a, 76b, and 76c will be in an inward position as in Fig. 13, 50 and all of their corresponding guides will be in an inward, operative, position; all the cams 76a, 76b, and 76c will be in an outer position as in Fig. 20 so that none of their corresponding yarn guides will have yarn taken therefrom; or any 55 individual one of the yarn guides will be in one or the other of such positions with the remaining yarn guides in the remaining one of said positions as in various ones of Figs. 14-19; all as exemplified in Figs. 13-20. It will thus be 60 apparent that if the yarn guide associated with the cam 76a carries red yarn, the yarn guide associated with the cam 76b carries white yarn, and the yarn guide associated with the cam 76c carries blue yarn, the design portions of yarn 65 of these three colors may be readily formed side by side, in pairs, or individually, as may be desired, and that whenever a design portion of a particular yarn is not being formed, its yarn guide will be held outwardly of the cylinder and 70

the yarn will be caught into the fabric until a design portion is again being made. While the resulting vertical floats may be left in the fabric in certain instances, they are commonly cut away after the formation of the fabric. In the present instance the annulus 132 repeats the succession of protuberances as indicated throughout its extent, the sequence continuing in regular order up to the yarn guide associated with cam 10 16a, but it will be understood that various other arrangements may be utilized.

As will be apparent, only slight rotative movements of the annulus 132 are necessary to effect the selective action desired. In the present instance, such movements are effectuated thru the medium of a bell-crank lever 141 having one end pivoted at 142 on a bracket 143, which is secured to the annulus 132, and being centrally pivoted at 144 on the ring 31. On its free end it carries 15 rearwardly diverging cam portions 146 and 147. In order to swing the lever 141 thru action upon one or the other of cam portions 146 and 147, there is provided a small drum 149 rigidly mounted on an arm 150 carried by the central post of 20 the rotary spider 12, and having a series of (eight, in the present instance) rows 151 of holes 152. In a suitable one of the holes of each of some or all of the rows, there is disposed a pin 153 in the form of a frictional insert. The drum 25 149 and the pins 153 are so arranged that a pin 153 in that one of the rows 151 which is in an outward position will pass between the divergent part of the cam portions 146 and 147, and, depending on its disposition, will bear either 30 against the cam portion 146 or against the cam portion 147 to swing the lever 141 (and consequently the ring 132) in one direction or the other, or will pass between the convergent part of the cam portions so as not to move the lever 35 40 45 50 55 60 65 70 75 80 85 90 95 100 105 110 115 120 125 130 135 140 145 150 155 160 165 170 175 180 185 190 shoulders 204 and 205, adapted to be engaged by a cam 206 when the rocker element is, respectively, in one or the other of two positions to raise the rocker element and the needle partially 5 (to tucking position) or fully (to knitting position), or to lie inwardly of the cam so that the rocker element will not be advanced at all, depending on a three-position selection of the rocker element 203 resulting from a previous positioning of a slidable element 207. A series of 10 cams 208 are disposed about the machine at points where needle selection for reception of yarn either from a reciprocating yarn guide or from rotating main yarn feed are desired; and 15 in advance of each cam 206 there is provided mechanism for imparting a three-position selective movement to the slidable element 207 to set the rocker element 203. Needle retracting cams 208 are provided to complete each needle 20 wave initiated by a cam 206, and, after each of 25 these, a restoring cam 209 for the rockers is provided. The selective operation of the slidable elements 207 is controlled by drums each disposed between a cam 209 and a cam 206 and rotatably 30 mounted within a housing 210. The setting of the drums is effectuated at suitable periods, as once in each revolution of the machine; in accordance with a line of configurations on a pattern band 211 by means of suitable mechanism 35 including a picker 212. The cams 206 and 209 are carried on a cam ring 215 rotated by a pinion 216 meshing with an annular gear 217, and the cams 208 are carried on a cam ring 218 mounted on an annular member 219 which carries the 40 housings 210 and various operating cams for the selective mechanism, and which is caused to rotate with the cam ring 215 thru suitable means and by a pinion 220. The pinions 216 and 220 are carried on a shaft 220' driven from a suitable 45 source of power (not shown). The construction and operation of the pattern band 211 and rockers 203 and of all the intervening and associated elements is similar to that shown in Figs. 42-53 of my United States Patent No. 2,025,463, and 50 described therein. Mounted on the rotating annulus 219 is a rotary framework 221 on an upper portion 222 of which there are carried bobbins 223, yarns from each of which is conducted by suitable means in the usual manner to one of a 55 plurality of main-yarn feeds 224, each removably mounted on an annulus 225 carried from the rotating framework 221 by means of posts 233.

Supported from the needle cylinder 200 is a 60 sinker bed 226 in the slots 227 of which are slidably disposed sinkers 228 having butts 229 projecting into a cam groove 230 in a sinker cam ring 231 supported from brackets 232 extending inwardly from a portion of the rotary framework 221.

Beneath the annulus 225 there is provided a bed 234, formed with a series of slots 235 in desired one of which there are slidably disposed for radial sliding movement, yarn-guiding means 236 each 5 having an independent yarn-guiding portion 237. The portions 237 of the yarn-guiding elements 236 are slidable between an outward position shown in full lines in Fig. 24, and an inward yarn-feeding position shown in dotted lines in Fig. 24; and in 10 order to effectuate such sliding movement, and, in the present instance, to effectuate it in a selective manner, each element 236 has pivoted near its outer end at 238 a rocker element 239 the inner end of which carries teeth 240 and the outer 15 end of which carries a cam-engaging portion 241.

The rockers, as originally constructed, ordinarily are desirably provided with a plurality of frangible teeth (five in the present instance), and certain of these teeth are broken off on individual rockers when it is desirable to have varying selectivity of different rockers pursuant to certain settings of a control mechanism, all as is well understood in the art. In order to select the rockers, there are provided a plurality of selector cams 242 (five in the present instance) pivotally mounted in an opening 243 in the annulus 225 and each individual to a tooth in a given position when a yarn-guiding member 236 is disposed outwardly. These cams are adapted to have their operative faces resiliently held upwardly by springs 243' 15 but to be pressed downwardly when an insert 244 is in a juxtaposed hole 245 in a drum 246. Inserts will be suitably disposed in the holes 245 and the drum will be rotated step-by-step to bring successive rows of holes directly above the 20 cams 242 so as to depress one or more of these cams if an insert or inserts are in a predetermined one or ones of the holes of the row. The drum 246 is carried on a shaft 247 suitably journaled in a bracket 248 secured to the annulus 225; and the 25 shaft is adapted to be turned step-by-step thru the medium of a pawl 249 bearing against a ratchet 250 on the end of the shaft 247, and carried from an upright 251 which is hung from a pin 252 carried on an arm 253 which is integral 30 with a shaft 254 carrying at its outer end a similar arm 255. The pawl 249 is pivoted at 256 to a plate 256' which is rotatably mounted on the shaft 247, and is connected with the rod 251 thru the medium of a pin 257 in such manner that as the 35 rod is raised due to the raising of the arm 253 the pawl will rotate the ratchet an extent corresponding to the distance between successive rows of holes 245. The shaft 254 is supported on the 40 rotatable framework by means of brackets 258. It will be appreciated that any desired number 45 of drums 246 may be employed, each of these drums being equipped with step-by-step rotating mechanism. In order to swing the arm or arms 255, there is provided a bell crank pivoted 50 at 260 on a stationary support and so arranged that one end 261 may be swung into the path of movement of the arm or arms 255 when a nub 262 on a pattern chain 263 is against the other end 263' of the bell crank. The end 261 and the 55 arm or arms 255 are so formed that engagement of an arm 255 by the end 261 will be just sufficient to cause a stepping action by the pawl and ratchet of such extent that one row of holes 245 will be moved out of operative position, and 60 a succeeding row of holes 245 will be moved into operative position. Prior to the passage of a set of selector cams the rockers will all be swung to the position shown in Fig. 24 by means of a cam 264. Dependent upon the arrangement of 65 inserts in the drum 246 and the position of the drum, such rockers as have teeth in the path of an operative selector cam 242 will be swung on their pivots 238 to bring the cam-engaging portions 241 thereof in the path of a cam 265 carried on the annulus 225 and arranged to move the rocker and its yarn guide inwardly so as to dispose the yarn guide in a yarn-feeding position. A restoring cam 266 acting on butts 267 on the members 236 is carried on the annulus 225 following 70 the selector cam 242. If a plurality of sets of selector cams and drums are employed, a restoring cam 266 and an advancing cam 265 will be provided in connection with each set of selector cams, as will be readily understood. The main 75

yarn feeds 224 will be so disposed that none of them will be present in the intervals between the operation of a cam 265 and the operation of a cam 266. Accordingly, there will be no danger of the 5 main-yarn feeds contacting and breaking a yarn-guiding element 236.

The bed 234 is arranged for reciprocation and is freely supported on a stationary annulus 270, which in turn is freely supported by an annulus 10 271 carried by the rotating brackets 232. In order to hold the annulus 270 against undesired rotation, and at the same time to permit the sinker cam ring 231 to rotate with the rotary framework, the brackets 232 carry bearings 272 thru which 15 there extends a shaft 273 carrying on its end pinions 274 and 275 adapted to mesh, respectively, with an annular gear 276 carried by the sinker bed 226 and an annular gear 277 secured to the annulus 270. The gear 276 is secured to the 20 sinker bed in the present instance, but may be freely mounted thereon and connected with adjusting mechanism, for a purpose to be herein-after described. It is to be noted that yarn for the yarn guides 237 is drawn thru holes 278 in the 25 annulus 270 from bobbins 279 disposed on brackets 280 which extend outwardly from the annulus 270. Reciprocation of the annular plate 234 is caused at suitable periods in the rotation of the framework 221, by means of cams 281 and 282 30 acting thru the medium of a three-armed member 283 which is pivoted at 284 on a projection 285 from the annulus 270. The upper arm of the member 283 receives a pivot pin 286 from a plate 287 secured to the flange 288 on the annular plate 35 234; and the two lower arms carry externally and interiorly, respectively, rollers 289 and 290 in the paths of movement of the cams 281 and 282. The plate 287 is secured by screws adapted to be inserted in any of a plurality of sets of 40 holes 290' in the flange 288. A plurality of cams 281 and 282 are provided in the present instance so that movement of the annular plate 234 in the direction of the framework, and in the opposite direction, respectively, will each occur at a plurality of periods during the rotation of the framework 221. As will be seen, a surface 291 of a cam 281 will act to raise the roller 289, a surface 292 of a preceding cam 282 allowing a roller 290 to recede at the same time; and a surface 293 of a 45 cam 282 will act to raise a roller 290, a surface 294 of a cam 281 allowing a roller 289 to recede at the same time. Thus oscillating movements of the member 283 will occur at fixed intervals with the result that the annular plate 234 will reciprocate. The reciprocation of the annular plate 234 results in drawing forwardly and/or rearwardly along the line of the needles such yarn guides 237 as are in an outward position. Thus, 50 any needles which have been raised either fully (to knitting position) or partially (to tucking position) will receive yarn from such yarn guide during either its forward movement or its return movement, or both, depending on whether the needles are in raised position during both movements, or only during one such movement.

In the form of construction exemplified in Figs. 27, 28, and 29, there is provided a needle cylinder 300 in the slots 301 of which there are provided a series of latch needles 302. In the present instance, the needle cylinder is stationary, and there is provided rotating means operable to selectively control the needle movement in any of a variety of well-known or suitable ways. Such means may, for instance, comprise cams and suitably-formed pattern wheels or various types of 78

jacquard mechanism, or other desired types of control means may be utilized; but the machine in the present instance is to be understood as exemplified in a form wherein the lower portion thereof not shown corresponds to the lower portion of Fig. 23, and as embodying a rotary framework generally similar to that of Figs. 1 and 23, and including posts 303 extending upwardly from a rotating annulus similar to the annulus 219. Main yarn feeds 304 are carried from portions 10 305 of the rotary framework.

Mounted on the cylinder 300 is a sinker bed 306 carrying sinkers 307 adapted to be operated in the usual manner by a sinker cam ring 308 supported thru the medium of brackets 309 from 15 the posts 303. The posts also carry the annulus 310 at points above the brackets. The annulus 310 is formed with a ledge 311 which freely supports a bed 312 adapted to be held stationary with respect to the needle cylinder by means comprising a shaft 313 rotatably supported by the bracket 309 and carrying a lower pinion 314 meshing with an annular gear 315 on the sinker bed 306, and a pinion 316 meshing with an annular gear 317 on the bed 312.

The bed 312 is formed of a series of slots 318 in suitable ones of which there are slidably disposed portions 319 of yarn-guiding elements 320 an inner portion 321 of each of which is swingable and carries a yarn-guiding portion 322 and an operating wing 323. Swinging movements of member 321 will result in drawing yarn back and forth past a group of needles in such position that if all or some of the needles of this group are in yarn-receiving position, yarn will be fed thereto. 35 Swinging movements of the members 321 are effectuated in the present instance by means of pins 324 and 325 carried on an annulus 326 connected by brackets 327 with a rotating annulus 328, which is supported from and driven by the 40 posts 303. Edges of the wings 323 in the path of these pins are formed with cam surfaces 329 and 330 so that when a pin 324 passes the wing 323 of a member 321, the wing will be swung upwardly and the yarn-guiding portion 322 will be 45 swung rearwardly; and so that when a pin 325 engages a surface 329 on the wing 323 of a member 321, the yarn-guiding portion 322 thereof will be swung forwardly. The mounting means for each member 321 includes a pivot pin 331 and a 50 lock nut 332 whereby the portion 321 may be secured to the portion 319 with sufficient tightness so that it will not tend to swing beyond the position in which it is placed by a pin 325 and so that the tension of the yarn extending thereto 55 will not pull it out of position. In order to assure that the yarn guiding portions 322 will follow the curve of the line of needles during their movements, each of these members is made of resilient material and is so formed that there will be a 60 tendency for the portion 322 to move inwardly. Inward movement of this portion, however, is limited by an annular flange 333 against which the tip 334 of each member 321 bears. The flange 333 is formed on a stationary annulus 335 connected by brackets 336 to the bed 312.

In order to move the yarn guiding portions 322 into and out of active position at desired periods in the operation, each slidable portion 319 carries a rocker 340 which is pivoted thereto at 71 341 and in the present instance is similar in all respects to a rocker 239 as heretofore described. The plate 328 carries a set of selector cams 342 and a drum 343 with inserts 344. The selector cams and the drum and their associated elements 7

are in the present instance similar in all respects to the selector cams 243 and the drums 246 of Figs. 23-26, and are operated by similar means including a pawl 345 operating on a ratchet 346. 5 A plurality of sets of selector cams and drums may be provided. The plate 328 carries a restoring cam 347 similar to the cam 265, a restoring cam 348 similar to the cam 266, acting on butts 349 of the slideable portions 319 for each set of selector cams. A cam 350 corresponding to cam 264 is also provided.

Accordingly, by means of the control mechanism including the selector cams 342, the yarn-guiding elements 320 may be moved between the 15 full-line position and the dotted-line position of Fig. 29 so that a yarn guiding portion thereof may be in active position during the formation of design and may be in inactive position when designs are not being formed. The main yarn feeds 304 are removably carried from the ring 326, as shown.

It is sometimes desirable that a yarn guide which supplies yarn for reception by a group of needles at one portion of a needle bed during one 25 stage of operation should supply yarn for reception by a group of needles at a different portion of the needle bed at another stage of the operation so that, for example, design portions of yarn of a single color or character may be provided at 30 different parts of the fabric without the necessity for the provision of an undue number of yarn guides, and it is also desirable that yarn from a single yarn guide be incorporated in the fabric in a particularly simple manner to provide diagonal effects, or that other variations in the 35 range of action of a yarn guide or a set of yarn guides be provided for; and there are provided in accordance with the invention, in certain of its aspects, automatic means for accomplishing such 40 purposes.

In the form of construction exemplified in Figs. 30-34, there is provided a form of machine whereby such results are accomplished, and wherein there is provided, in addition, means for reciprocating the yarn guides.

The particular form of machine exemplified is the form of machine disclosed in Figs. 1-21 of my said Patent No. 2,130,769, with the exceptions noted below. In general, the modifications of 50 said machine include the omission of the travelers shown at 43 in said patent; a reduction of the number of main yarn feeds to four, with a corresponding increase in the size of the pattern wheels; the provision of four sets of plunger-cams, so that a set is provided for each auxiliary-yarn wave (four being provided); an increase in the extent of these plunger-cams so as to provide for operability during reciprocating movements of the yarn fingers; the omission of the manually operable member 19 of said patent and associated parts; and the provision of the mechanism described in detail below. The machine includes a stationary needle cylinder 408, rotating parts indicated generally at 401 and driven from a suitable source of power (not shown), an interior member 402 whereby yarn guides in the form of pivoted fingers 403 are mounted, and other elements, an understanding of the construction and operation of which may be had by reference to 60 my said Patent 2,130,769. The rotating means 401, in the present instance, includes four main-yarn feeds 404, each corresponding to a main-yarn feed 42 of my said Patent 2,130,769, and also includes eight pattern wheels 405 each of 65 70 75 which has twice the circumference of a pattern

wheel 34 of my last-mentioned patent. In the exemplified form of machine, no travelers corresponding to the travelers 43 of my last-mentioned patent are provided, but there is provided, following each pattern wheel which follows a 5 main yarn feed, a finger actuating unit 406 which is similar to the unit 65 of my last-mentioned patent, except that the plunger cams are formed with arcuate bearing surfaces which are extended longitudinally an amount greater than 10 the amount of reciprocation imparted to the finger carrying member 402 in the manner hereafter to be described. The cams of the units 406 are selectively positioned, as by selector mechanism indicated generally at 406a and corresponding to that of my last-mentioned patent, to cause the yarn-guiding end of a selected finger 403 to be swung outwardly as a plunger cam passes so as to permit the yarn to be moved in front of the needles in position to be received by selected 20 needles. Each selected finger may thus be held outwardly by its cam a sufficient time for the needles previously raised by a pattern wheel to have been retracted by a succeeding stitch cam, but thereafter to be released so that it will go behind the line of needles before a succeeding 25 main-yarn needle wave occurs.

In order to shift the fingers to desired positions with respect to the needle bed at desired times, there is provided pattern controlled shifting 30 mechanism which operates on an annular rack 407 corresponding to the rack 15 of my last-mentioned patent. Fixedly secured to the rack 407 and disposed above the same is a sprocket wheel 408 from which a sprocket chain 409 extends to 35 a sprocket wheel 410 keyed to a shaft 411 which is rotatably mounted within a tubular post 412 carried from the stationary framework 413 of the machine. The shaft 411 carries at its lower end a gear 414 meshing with a worm 415 which is 40 splined on a shaft 416 carrying a pair of ratchet wheels 417 and 418, the teeth of which are disposed in opposite directions as indicated in Figs. 32 and 34. A pawl 419 is provided in association with the wheel 417, and an oppositely directed 45 pawl 420 is provided in connection with the ratchet wheel 418. The pawls 419 and 420 are each fixedly secured on a rod 421 which is mounted, in a manner hereinafter described, for rotative movement pursuant to the positioning of 50 a link 422 which is pivotally connected at 423 to a link 424 which in turn is pivotally connected at 425 to an operating arm 426 which is pivoted at 427. The link 424 is composed of two telescoping members non-separably connected in a telescoping manner and normally held in extended relationship by a spring 428 against the pressure of which the pawls may be lifted as they slide over the teeth. The arm 426 is normally swung in a counter-clockwise direction (Fig. 32) by means 60 of a spring 429 and is adapted to be swung in a clockwise direction by projections on a pattern chain 430. The pattern chain 430 is rotated slowly when compared with the linear speed of rotation of the rotating parts 401 of the machine 65 by means of a reduction gear 432 which is adapted, when a clutch mechanism hereinafter to be described is engaged, to drive a pinion 433 meshing with a gear 434 carried on one end of a shaft 435 on which the pattern-chain sprocket 70 75 75 436 is mounted. The arm 426 is formed with a nub 437 having a cam surface 438 of such nature that the arm will be lifted as a projection on the pattern chain moves under the nub 437. The pattern chain carries high projections 439 adapt-

ed to move the arm 426 to the position of Fig. 32 and low projections 440 adapted to move the arm 426 to the position of Fig. 33. It will be noted that both types of projection are made of varying extent longitudinally of the chain so that they will be effective for greater or lesser periods when the chain is moving normally.

The rod 421 is rotatably carried on one end of a lever 441, which is rotatably mounted on the shaft 416. This lever is given an oscillating movement by means of an eccentric 442, the yoke 443 of which is freely connected to the other end of the lever 441 at 444. The eccentric 442 is keyed to a shaft 445 which is rotated from the 15 rotating parts 401 by means of gearing 446. The lever 441 will accordingly be given an oscillating movement. If the rod 421 is in the position shown in Fig. 33, the ratchet wheels 417 and 418 will not be affected by the oscillation of the lever 20 441. When, however, the rod 421 is in the position of Fig. 32, the pawl 420 will act against the teeth of the ratchet wheel 418 to advance the wheel one tooth in a clockwise direction for each 25 rotation of the shaft 445; and when the rod 421 is in the position of Fig. 34, the pawl 419 will act to advance the ratchet wheel 417 in a counter-clockwise direction one tooth for each rotation of the shaft 445.

As above set forth, the rotative position of the 30 rod 421 depends on the position of pattern chain 430 and it is to be noted that the rod may be continued in any position for short or medium-length periods depending on the extent of a projection on the pattern chain or of a space between projections longitudinally of the chain. There will, however, be times when it is desirable to have the pattern chain 430 remain in a given position, as for example, in the position shown in Fig. 33, for extended periods. To this 35 end, the connection between the gears 432 and 433 includes a clutch mechanism 448 which may be disconnected by the outward movement of a rod 449, the end of which is formed with a groove 450 which receives the forked end 451 of a bell-crank lever 452 pivoted at 453 on a stationary piece 454. The arm 455 of the lever 452 is adapted to be swung to disconnect the clutch 448 by 40 nubs 456 on a pattern chain 457 operated from the rotating parts 401 by means of reduction 45 gearing 458.

In order that the member 402 and the yarn-guiding fingers 403 carried thereby may be reciprocated regardless of the position to which they may have been shifted, the worm 415 is 50 splined on the shaft 416 for sliding movement, and is connected by a link 460 to a pin 461 which is eccentrically mounted on a wheel 462 driven by gearing 463 from the rotating parts 401. It will be appreciated that the reciprocatory movements of the worm 415 longitudinally of the splined shaft 416 will result in reciprocatory rotative movements of the gear 414, and, thru the medium of the sprocket chain 409 and the gearing connecting the rack 407 with the yarn finger-carrying member 402 as described in my last mentioned patent, will result in reciprocatory rotative movement of member 402 with consequent reciprocation of the yarn fingers carried thereby. Such yarn fingers as have their yarn-guiding ends inside the line of the needles will not 55 position the yarn for reception, but such yarn fingers as have their yarn-guiding ends operated by one of the cams of a unit 406 will position the yarn for reception by the needles during their reciprocatory movements in one or the other di-

rection, or both. In this manner there is provided a machine wherein the position of the yarn fingers can be shifted, and wherein the yarn fingers may be reciprocated back and forth regardless of the position to which they are shifted. 5

Shifting mechanism embodying the invention may be employed in connection with forms of construction other than those having reciprocable yarn guides, or the like. In Figs. 35 and 36 there is exemplified a form of construction which is similar in all respects to the form of construction disclosed in Figs. 1-21 of my said Patent 2,130,765, except that the member 19 and the associated parts are omitted, and that there is provided pattern controlled shifting mechanism 10 operating on a rack 407 corresponding to the rack 407, and to the rack 15 of my last-mentioned patent. The shifting mechanism is generally similar to that of Figs. 30-34 hereof, except that the reciprocating mechanism is omitted, and that, instead of the worm 415, there is provided a worm 500 which has no longitudinal shifting movement and which is keyed to a shaft 501 which is shorter than the shaft 416 and which does not provide for longitudinal movement of the worm, but which is otherwise similar to the shaft 416. The remaining parts of the shifting mechanism are similar in all respects to the other parts of the shifting mechanism illustrated in Figs. 30-34 and are indicated by 20 30 similar reference numerals with the addition of the subscript f. Full understanding of the construction and operation of the machine will be had from my last-mentioned patent, reference being had to Figs. 30-34 of the present case and 35 the description thereof hereabove.

In general, it may be said that the machine includes a stationary needle cylinder 502; yarn-guiding fingers 503; main yarn feeding means 504; traveler means 505, and pattern wheels 506, 40 all similar in number, construction, size, and operation to the corresponding parts of my last-mentioned patent; latch needles 507 similar to those of my last-mentioned patent, and other elements all of which will be fully understood in 45 the light of the foregoing.

Various of the forms of construction contemplated by the invention in various of its aspects, and including certain of the forms of construction exemplified, may likewise be equipped with 50 yarn-guide-shifting mechanism. In Fig. 37, there is exemplified a form of construction which is similar to the form of construction exemplified in Figs. 23-26. Reference may be had to such figures and the description of the machine 55 illustrated therein for understanding of the parts not specifically illustrated in Fig. 37, and of the construction and operation of the parts not specifically referred to below. In Fig. 37 parts corresponding to those of Figs. 23-26 are indicated 60 by similar reference numerals distinguished by the subscript g. The form of construction of Figs. 23-26 is modified, in that the gear 276 is omitted and the gear 273g is disposed at a lower 65 position, the shaft connecting this gear with the gear 275g being extended for this purpose. The gear 273g meshes with an annular gear 600 on a bracket 601 freely supported on a ledge 602 carried from a post 221g which forms a part of the rotating framework of the machine. The bracket 601 carries a gear 603 meshing with a pinion 604 carried on one end of a shaft mounted in a bearing 606 carried by the post of the framework 221g. At the other end of the shaft carrying the gear 604 is a pinion 607 meshing

with an annular gear 608 carried on an annulus 609 which is freely supported on a ledge 610 carried by the posts of the framework 221g. The member 609 is formed with teeth 611 which mesh with a worm 612 similar to the worm 500 and keyed to a shaft 613 carrying ratchet wheels 411g and 418g adapted to be operated by mechanism similar to the mechanism which operates the ratchet wheels 417 and 418 and exemplified in connection with the construction of Figs. 30-34, the parts being indicated by similar reference numerals distinguished by the subscript *g*. Rotation of the worm in one direction or the other results in shifting the annulus 609 and—thru the medium of the exemplified gearing—the plate 234g on which the yarn-guiding elements are carried. The construction and operation of the machine of Fig. 37 will be clearly apparent from the foregoing when considered in connection with the description of the machines exemplified in Figs. 23-26, Figs. 30-34, and Figs. 35-36.

There is shown in Figs. 38 and 39 a particularly simple form of machine wherein the needle cylinder 805 carries in its slots 806 a series of latch needles 807. The majority of these needles are formed with butt portions 808 which project from the needle slot only to a line 808', and each of which is formed with a shoulder 809 adapted to be engaged by one of a plurality of cams 810 each of which moves in advance of a main-yarn feed 811. At a given portion of the periphery of the needle cylinder certain of a group of the needles—alternate ones of the needles of the group in the present instance—are formed with butts 808a each having a shoulder 809 adapted to be engaged by the cams 810, and having also near their upper end a projection 812 extending beyond the line 808' and provided with a shoulder 813 adapted to be engaged by a cam 814. The cams 810 and 814 are mounted on a rotary cam ring 815 carried on an annulus 816 which is driven by mechanism such as heretofore exemplified, or by other suitable means. The cam 814 is mounted on this cam ring in the present instance in such a manner that it may move from active to inactive position by suitable manually-operated or automatic means. In the present instance it carries posts 817 and 817' slidably mounted in the cam ring; and the post 817 is formed with an annular recess 818 in which there is set one end of a bell-crank lever 819 pivotally supported on the cam ring at 820. One arm 821 of this lever extends outwardly of the rotating parts so as to be suitably operated, as for example as a pattern chain, carried on a stationary mounting in a manner which will be readily apparent to those skilled in the art. The main yarn feeds 811 in the present instance draw yarn from bobbins 823, the cams 810 serving in the present instance to raise the needles to fully advanced position so as to knit such yarn in a jersey fashion. For incorporation of auxiliary yarn in design portions or otherwise at one side of the tubular fabric formation, there is provided a yarn guide 825 which is mounted for arcuate reciprocatory movement and also for in-and-out movement past the line of needles. For the reception of yarn from the yarn guide 825, certain of a group of needles (alternate ones in the present case) are advanced by the cam 814 when in place so as to dispose the needles—those having projections 812—in a particularly advanced position for the laying-in of yarn from the yarn guide 825. The yarn guide 825 is carried on a

stem 826 which is pivotally secured at 827 to a lug 828 on an arcuate member 829. The arcuate member 829 is slidably mounted in a slot 830 in a disc 831 which, while supported from the rotary framework, does not partake of the rotary movement. It is to be observed that the bobbins 823 are mounted on a support 832 carried on a rotary framework 833 which in turn is carried on the rotating annulus 816. The disc 831 is carried by brackets 835 secured to an annulus 836 which is freely supported on a ring 837 forming part of the rotary framework. Rotation of the disc 831 is prevented, however, by a pair of rollers one of which, 838, is secured to the needle cylinder 805 and the other of which, 839, is carried on an arm 15 840 which depends from the disc 831. The fabric formed on the machine extends between these rollers so that the formation of a tubular fabric is not interfered with; but the roller 838 serves, nevertheless, to prevent the disc 831 from partaking in the rotary movement of the annulus 816 and the framework. The disc 831 is centered by means of a shaft portion 841 forming a part of the rotary framework.

The disc 831 carries a pinion 842 which meshes 25 with gearing 843 on the arcuate member 829 and also with gearing 844 on an arcuate member 845 of smaller radius which is slidably mounted in a slot 846 in the disc 831. As will be seen from Fig. 39, rotative movement of the arcuate member 845 in a clockwise direction will result in rotative movement of the arcuate member 829 and the yarn guide 825 in a counter-clockwise direction and rotative movement of the arcuate member 829 in a counter-clockwise direction will 30 result in rotative movement of the arcuate member 845 in a clockwise direction. In order to impart reciprocatory movement to the arcuate member 829 and the yarn guide 825, there is provided operating mechanism which in the present instance is carried on a plate 847 secured to the portion 848 of the rotary framework. This mechanism comprises a plunger contact member 849 set in a slot 850 in the plate 847 and normally thrust outwardly by a spring 851, the outward movement being limited by a pin 852 extending thru a slot 853 and held against outward movement by the outer end of the slot. When in this outer position, the plunger contact member 849 is adapted to contact a pin 854 on the arcuate element 845 as the plate rotates and to thrust the arcuate element in a counter-clockwise direction (Fig. 39). After the arcuate element 845 has been moved a suitable amount, a cam portion 855 engages the pin 852 and draws 40 the member 849 inwardly to the position where it no longer engages the pin 854. The arcuate element 829 also carries a pin, which is shown at 856 and which extends upwardly a greater distance than the pin 854. The plate 847 carries, 45 on the side thereof opposite the side in which the slot 850 is formed, a second plunger contact member 857 which lies on the top of the plate and accordingly is in a plane above the plane of the plunger contact member 849, the pin 854 terminating below this plane so that the plunger contact member 857 will not engage the pin 854. The member 857 carries a depending pin 858 extending into a slot 859, and is pressed outwardly by a spring 860. Accordingly, at each rotation 50 of the plate 847, the member 857 will engage the pin 856 and move the arcuate member 829 in a clockwise direction (Fig. 39) until the pin 858 is engaged by the cam 855 to draw the member 857 arcuately sufficiently to clear the pin. 55 75

The bracket 861 provides stops in the path of pins 854 and 856 to limit the movement of the arcuate members 829 and 844.

It will accordingly be seen that the yarn guide 825 completes a reciprocation once in each rotation of the cam ring 815, it being observed that the main yarn feeds are so spaced that during the clockwise rotation of the arcuate member 829 (Fig. 39) and the yarn guide no main yarn feed will pass.

The yarn guide 825 draws auxiliary yarn from a bobbin 863 supported from the disc 831 by a bracket 864. The yarn guide is normally held inside the row of needles by means of a spring 865, and is in this position at each end of its reciprocatory movement. It is thence thrust into yarn-feeding position in front of the line of needles by means of a cam member 866 mounted on the disc 831 and adapted to bear against a nub 867 at the rear of the stem 826, so that at the beginning of each of its forward and return movements the yarn guide will be thrust outwardly and held in a yarn-feeding position until toward the end of such movement, the stem swinging on the pivot 827 during the inward-and-outward movement of the yarn guide. As will be seen from Fig. 38, two cams 814 are provided in the present instance, one being disposed to partially advance certain needles (those needles which have projections 812) for reception of yarn during the forward movement of the yarn guide and the other serving to advance the same needles for reception of yarn during the return movement of the yarn guide. A plurality of retracting cams, of the character of ordinary stitch cams, are provided, one such retracting cam being provided in the present instance for retraction of the needles after each reception of yarn either from a main-yarn feed or from the yarn guide 825. It is to be observed that ordinary long- and short-butt needles may be employed if desired.

Since certain changes may be made in the above construction and different embodiments of the invention could be made without departing from the scope thereof, it is intended that all matter contained in the above description or shown in the accompanying drawings shall be interpreted as illustrative and not in a limiting sense.

It is also to be understood that the following claims are intended to cover all of the generic and specific features of the invention herein described, and all statements of the scope of the invention which as a matter of language might be said to fall therebetween.

I claim.

1. In a circular knitting machine, a needle bed, a series of needles on said bed, yarn-feeding means, said yarn-feeding means and said bed being arranged for relative rotative movement, yarn-guiding means, said yarn-guiding means and said bed being arranged for relative movement such that yarn from said yarn guide will be successively drawn past a portion of said bed in opposite directions, means to cause at least certain of said needles to receive yarn from said yarn-feeding means, and means to cause certain of said needles to receive yarn from said yarn-guiding means during the drawing out of yarn in one direction and to cause certain of said needles to receive yarn from said yarn-guiding means during drawing out of yarn in the reverse direction, said means for causing yarn to be received

from said yarn-feeding means and for causing yarn to be received from said yarn guiding means being simultaneously operated.

2. A knitting machine comprising a needle bed, a series of needles thereon, means to feed yarn into position for reception by the needles of said series, means reciprocable with respect to said bed to feed other yarn into position to be received by certain of said needles while the reciprocable means moves in one direction and to feed said other yarn into position to be received by certain of said needles while the reciprocable means moves in the opposite direction, means to reciprocate said reciprocable means, said reciprocable means having an extent of movement less than the extent of said series of needles, means to manipulate at least certain of said needles for reception of yarn from the first-mentioned yarn-feeding means, and means including unidirectional cam-means to manipulate certain of said needles for the reception of yarn from said reciprocable means pursuant to the movement thereof in both directions.

3. A knitting machine comprising a needle bed, a series of needles thereon, means to feed yarn into position for reception by the needles of said series, means reciprocable with respect to said bed to feed other yarn into position to be received by certain of said needles while the reciprocable means moves in one direction and to feed said other yarn into position to be received by certain of said needles while the reciprocable means moves in the opposite direction, means to reciprocate said reciprocable means, said reciprocable means having an extent of movement less than the extent of said series of needles, means to manipulate at least certain of said needles for reception of yarn from the first-mentioned yarn-feeding means, selective means for manipulating certain of said needles for the reception of yarn from said reciprocable means pursuant to the movement thereof in both directions, and means responsive to the last-mentioned means to control the operation of said reciprocable means.

4. A circular knitting machine comprising a rotatable member, a non-rotating member, one of said members comprising a needle bed and the other of said members comprising primary yarn-feeding means, means to cause rotative movement of the rotatable member, a series of needles on said bed, auxiliary yarn-feeding means having a reciprocating action with respect to said bed and being movable between a position at the rear of said needles and a position substantially in front of said needles; said auxiliary yarn-feeding means being adapted to move from a rearward position to a forward position and to carry yarn in front of the line of a group of needles in one direction and to move rearwardly and thereafter to move forwardly and carry yarn in front of the line of said group of needles in the other direction and to move rearwardly, and means to selectively operate said needles for the reception and incorporation of yarn from said yarn-feeding means.

5. A circular knitting machine comprising a rotatable member, a non-rotating member, one of said members comprising a needle bed and the other of said members comprising primary yarn-feeding means, means to cause rotative movement of the rotatable member, a series of needles on said bed, auxiliary yarn-feeding means having a reciprocating action with respect to said bed and being adapted to feed yarn into position to be received by certain of said needles when the rela-

5 tive movement of the auxiliary yarn-feeding means and the bed is in one direction and also to feed yarn into position to be received by certain of said needles when the relative movement of the auxiliary yarn-feeding means and the bed is in the other direction, said auxiliary yarn-feeding means being disposed in the path of movement of said primary yarn-feeding means at least at certain periods in the operation of said 10 machine and being movable out of said path of movement, means to move said auxiliary yarn-feeding means out of said path of movement for the passage of primary yarn-feeding means, and means to selectively manipulate the needles for 15 reception of yarn from said primary yarn feeding means and to selectively manipulate the needles for reception of yarn from said auxiliary yarn-feeding means during the relative movement of said auxiliary yarn-feeding means and said bed 20 in both said directions.

6. A circular knitting machine comprising a rotatable member, a non-rotating member, one of said members comprising a needle bed and the other of said members comprising primary yarn- 25 feeding means, means to cause rotative movement of the rotatable member, a series of needles on said bed, auxiliary yarn-feeding means having a reciprocating action with respect to said bed and being adapted to feed yarn into 30 position to be received by certain of said needles when the relative movement of the auxiliary yarn-feeding means and the bed is in one direction and also to feed yarn into position to be received by certain of said needles when the 35 relative movement of the auxiliary yarn-feeding means and the bed is in the other direction, said auxiliary yarn-feeding means being normally disposed in the path of movement of said primary yarn-feeding means and being movable 40 out of said path of movement, cooperating means on said primary yarn-feeding means and said auxiliary yarn-feeding means for moving said auxiliary yarn-feeding means out of said path of movement during the passage of primary 45 yarn-feeding means, and means to selectively manipulate the needles for reception of yarn from said primary yarn-feeding means and to selectively manipulate the needles for reception of yarn from said auxiliary yarn-feeding means 50 during the relative movement of said auxiliary yarn-feeding means and said bed in both said directions.

7. A circular knitting machine comprising a rotatable member, a non-rotating member, one of said members comprising a needle bed and the other of said members comprising primary yarn-feeding means, means to cause rotative movement of the rotatable member, a series of needles on said bed, auxiliary yarn-feeding means having a reciprocating action with respect to said bed and being adapted to feed yarn into 55 position to be received by certain of said needles when the relative movement of the auxiliary yarn-feeding means and the bed is in one direction and also to feed yarn into position to be received by certain of said needles when the relative movement of the auxiliary yarn-feeding means and the bed is in the other direction, and means to selectively manipulate the needles for 60 reception of yarn from said primary yarn-feeding means and to selectively manipulate the needles for reception of yarn from said auxiliary yarn-feeding means during the relative movement of said auxiliary yarn-feeding means and said bed in both said directions, said manipulat-

ing means being adapted to arrange some or all of a group of needles for yarn reception prior to said relative movement in one of said directions and to maintain said needles so arranged until the completion of the relative movement in said 5 one of said directions.

8. A circular knitting machine comprising a rotatable member, a non-rotating member, one of said members comprising a needle bed and the other of said members comprising primary yarn- 10 feeding means, means to cause rotative movement of the rotatable member, a series of needles on said bed, auxiliary yarn-feeding means having a reciprocating action with respect to said bed and being adapted to feed yarn into 15 position to be received by certain of said needles when the relative movement of the auxiliary yarn-feeding means and the bed is in one direction and also to feed yarn into position to be received by certain of said needles when the 20 relative movement of the auxiliary yarn-feeding means and the bed is in the other direction, and means to selectively manipulate the needles for reception of yarn from said primary yarn-feeding means and to selectively manipulate the 25 needles for reception of yarn from said auxiliary yarn-feeding means during the relative movement of said auxiliary yarn-feeding means and said bed in both said directions, the speeds of said relative movements and said rotative movement being substantially commensurate.

9. A knitting machine comprising a needle bed, a series of needles thereon, means to feed yarn into position for reception by the needles of said series, means reciprocable with respect to said 30 bed to feed other yarn into position to be received by certain of said needles while the reciprocable means moves in one direction and to feed said other yarn into position to be received by certain of said needles while the reciprocable 35 means moves in the opposite direction, means to reciprocate said reciprocable means, said reciprocable means having an extent of movement less than the extent of said series of needles, means to manipulate at least certain of said 40 needles for reception of yarn from the first-mentioned yarn-feeding means, means to manipulate certain of said needles for the reception of yarn from said reciprocable means pursuant to the movement thereof in both directions, the first- 45 mentioned yarn-feeding means and said reciprocable yarn-feeding means being so arranged that one of said means may be moved out of the way of the other, and means to move said 50 one of said yarn-feeding means out of the way of said other thereof to permit said yarn-feeding means to pass one another.

10. A knitting machine comprising a needle bed, a series of needles thereon, means to feed 55 yarn into position for reception by the needles of said series, means reciprocable with respect to said bed to feed other yarn into position to be received by certain of said needles while the reciprocable means moves in one direction and to feed said other yarn into position to be received by certain of said needles while the reciprocable means moves in the opposite direction, means to reciprocate said reciprocable means, said reciprocable means having an extent of movement less than the extent of said series of 60 needles, means to manipulate at least certain of said needles for reception of yarn from the first-mentioned yarn-feeding means, means operable simultaneously with the aforesaid manipulating means to manipulate certain of said 65 needles.

- needles for reception of yarn from said reciprocable means pursuant to its movement in one direction, means operable simultaneously with the operation of the first-mentioned manipulating means to manipulate certain of said needles for the reception of said yarn from said reciprocable means pursuant to the movement thereof in said opposite direction, said reciprocable yarn-feeding means being mounted for movement out of yarn-feeding position, and means to move said yarn-feeding means to such position to prevent reception of yarn therefrom during the reception of yarn from the first-mentioned yarn-feeding means.
15. 11. A knitting machine comprising a needle bed, a series of needles thereon, means to feed yarn into position for reception by the needles of said series, means reciprocable with respect to said bed to feed other yarn into position to be received by certain of said needles while the reciprocable means moves in one direction and to feed said other yarn into position to be received by certain of said needles while the reciprocable means moves in the opposite direction, means to reciprocate said reciprocable means, said reciprocable means having an extent of movement less than the extent of said series of needles, means to manipulate at least certain of said needles for reception of yarn from the first-mentioned yarn-feeding means, means including unidirectional cam-means to manipulate certain of said needles for the reception of yarn from said reciprocable means pursuant to the movement thereof in both directions, and means to hold said reciprocable means out of yarn-feeding position during certain periods in the operation of said machine.
12. In a circular knitting machine, in combination, a needle bed, a series of needles on said bed, a yarn guide, means to mount said yarn guide, said mounting means and said bed being arranged for relative arcuate movement, and means to impart movement to one of said relatively movable members such that said yarn guide and said bed will partake of alternate arcuate movements in opposite directions with respect to each other, and means to cause yarn from said yarn-guide to be received by certain of said needles during arcuate movement in each direction, and means to cause other yarn to be received by certain of said needles at times interspersed with the times when they receive yarn from said yarn guides.
13. In a circular knitting machine, in combination, a needle bed, a series of needles on said bed, a yarn guide, means to mount said yarn guide, said mounting means being arranged for relative movement with respect to said bed, and means to impart movement to said mounting means such that said yarn guide will successively partake of movements in opposite directions along said bed, means to cause yarn from said yarn guide to be received by certain of said needles during each of said movements, means to manipulate said needles, said needle-manipulating means and said bed being mounted for relative rotative movement, and means to cause other yarn to be received by certain of said needles intermediate certain of the times when yarn is received from said yarn guide at least once in each relative rotation of said needle-manipulating means and said bed.
14. In a knitting machine, in combination, a needle bed, a series of independent needles on said bed, means to manipulate said needles, said
- needle-manipulating means and said bed being mounted for relative rotative movement, a yarn guide, yarn-guide carrier means, resilient means for mounting said yarn guide in such manner that it can be moved between yarn-feeding and non-yarn-feeding positions, said resilient means normally maintaining yarn guide in yarn-feeding position, and means forming a unit with said needle-manipulating means in said relative rotation to move said yarn guide out of yarn-feeding position.
15. In a knitting machine, in combination, a needle bed, a yarn guide, yarn-guide carrier means, resilient means for mounting said yarn guide in such manner that it can be moved between yarn-feeding and non-yarn-feeding position, said resilient means normally maintaining yarn guide in yarn-feeding position, yarn feeding means other than said yarn guide, and means associated with the last-mentioned means for moving said yarn guide out of said yarn-feeding position.
16. A knitting machine comprising a needle cylinder, a series of needles thereon, rotating yarn-feeding means, means reciprocable with respect to said needle cylinder to feed other yarn into position to be received by certain of said needles while the reciprocable means moves in one direction and to feed said other yarn into position to be received by certain of said needles while said reciprocable means moves in the opposite direction, means to reciprocate said reciprocable means, said reciprocable means including yarn guiding means movable radially of said cylinder, means to cause needle-reception of yarn from the first-mentioned yarn-feeding means, means adapted to be operated during the operation of said causing means to cause needle-reception of yarn from said yarn guiding means during the movement of the reciprocable means in both directions at certain periods in the operation of the machine when said yarn-guiding means is in an inward position but not when it is in an outward position, and means to control the radial position of said yarn-guiding means.
17. In a circular knitting machine, in combination, a needle bed, a series of needles on said bed, a rotating yarn guide, a reciprocating yarn guide, means to cause at least certain of said needles to receive yarn from said rotating yarn guide, and means to cause certain of said needles to receive yarn from said reciprocating yarn guide during its movement in one direction and to cause certain of said needles to receive yarn from said reciprocating yarn guide during its movement in the opposite direction, said means for causing yarn to be received from said rotating yarn guide and said means for causing yarn to be received from said reciprocating yarn guide being simultaneously operative.
18. In a circular knitting machine, in combination, a needle bed, a series of needles on said bed, a plurality of rotating yarn guides, a reciprocating yarn guide, means to cause at least certain of said needles to receive yarn from said rotating yarn guides, and means to cause certain of said needles to receive yarn from said reciprocating yarn guide during its movement in one direction and to cause certain of said needles to receive yarn from said reciprocating yarn guide during its movement in the opposite direction.
19. In a circular knitting machine, in combination, a needle bed, a series of needles on said bed, a rotating yarn guide, a plurality of reciprocating yarn guides, means to cause at least cer-

tain of said needles to receive yarn from said rotating yarn guide and means to cause needles to receive yarn from said reciprocating yarn guides, the last-mentioned means being operative to effect reception of yarn regardless of which direction a reciprocating yarn guide is moving.

20. A knitting machine comprising a needle bed, needles on said bed, means movable in one direction to feed yarn to some or all of a group 10 of needles and movable in the opposite direction to feed yarn to some or all of the needles of said group, means to impart movement to said movable means in said directions, means to manipulate said needles for yarn reception pursuant to the movement of said movable means in both directions, and means responsive to the operation of said manipulating means to control the extent of at least certain of the movements of said movable means.

21. A knitting machine comprising a needle bed, needles on said bed, means movable in one direction to feed yarn to some or all of a group of needles and movable in the opposite direction to feed yarn to some or all of the needles of said group, means to impart movement to said movable means in said directions, means to manipulate said needles for yarn reception pursuant to the movement of said movable means in both directions, and means dependent upon the needle manipulation to control the extent of said movements of said movable means.

22. A circular knitting machine comprising a needle bed, needles on said bed, means movable in one direction to feed yarn to some or all of a group of needles and movable in the opposite direction to feed yarn to some or all of the needles of said group, means tending to move said movable means first in one direction and then in the other, means to manipulate said needles for yarn reception pursuant to the movement of said movable means in both directions, means to selectively control the extent of movement of said movable means in said directions, and yarn-feeding means rotating about said bed during the operation of said movable means.

23. A circular knitting machine comprising a needle bed, needles on said bed, means movable in one direction to feed yarn to some or all of a group of needles and movable in the opposite direction to feed yarn to some or all of the needles of said group, means tending to move said movable means first in one direction and then in the other, means to manipulate said needles for yarn reception pursuant to the movement of said movable means in both directions, stop means for limiting the movements of said movable member, and means to selectively control the operation of said stop means.

24. A circular knitting machine comprising a needle bed, needles on said bed, means movable in one direction to feed yarn to some or all of a group of needles and movable in the opposite direction to feed yarn to some or all of the needles of said group, means tending to move said movable means first in one direction and then in the other, means to selectively manipulate said needles for reception of yarn from said movable means, and means including a part of said manipulating means for selectively controlling the extent of movement of said movable means.

25. A knitting machine comprising a needle bed, needles on said bed, means movable in one direction to feed yarn to some or all of a group of needles and movable in the opposite direction to feed yarn to some or all of the needles of said

group, means tending to move said movable means first in one direction and then in the other, means to selectively manipulate said needles for reception of yarn from said movable means, and means including said needles to selectively control the movement of said movable means.

26. A circular knitting machine comprising a needle bed, needles thereon, means movable arcuately along said bed in one direction to feed yarn to some or all of a group of said needles and movable arcuately in the opposite direction to feed yarn to some or all of the needles of said group, means to impart movement to such movable means in said directions, and means including mechanism rotating in only a single direction 15 to manipulate said needles for yarn reception pursuant to the movement of said movable means in both directions.

27. A circular knitting machine comprising a needle cylinder having a vertical axis, needles 20 on said cylinder, a yarn guide, means to swingably support said yarn guide for generally horizontal movement in an arcuate course past said needles, means to move said yarn guide thru an arcuate horizontal course past said needles in 25 one direction and thereafter to move said yarn guide in an arcuate horizontal course past said needles in the opposite direction, and means to cause yarn from the said yarn guide to be received by certain of said needles during the 30 movement of the yarn guide in said one direction and to cause yarn to be received from said yarn guide by certain of said needles during the said movement of said yarn guide in said opposite direction.

28. A knitting machine comprising a needle bed, a series of needles thereon, rotatable means to feed yarn into position for reception thereof by at least selected ones of said needles thruout the entire extent of said series, means movable 40 in one direction to feed yarn to some or all of a limited group of said needles and movable in an opposite direction to feed yarn to some or all of the needles of said group, means to cause movement to the second-mentioned yarn-feeding means in said directions, rotatable means to manipulate at least certain of said needles for reception of yarn from the first-mentioned yarn-feeding means, and rotatable means to manipulate certain of the needles of said group for 50 reception of yarn from the second-mentioned yarn-feeding means pursuant to the movement thereof in both directions.

29. In a knitting machine, a needle bed, needles on said bed, a dial, a plurality of yarn guides 55 slidably mounted on said dial, means to impart individual sliding movement to said yarn guides, means to reciprocate said dial, and means including said imparting means and said reciprocating means to cause said needles to receive 60 yarns from said yarn guides to form a desired type of fabric.

30. In a knitting machine, a needle bed, needles on said bed, a reciprocable bed, a plurality of yarn guides mounted on said reciprocable bed 65 for movement into position in which the yarn may be received therefrom by at least certain of said needles, selective means for imparting such movement to said yarn guides, means to reciprocate said reciprocable bed while at least certain 70 of said yarn guides are in said position so as to cause the same to feed yarn into position for needle reception, and means to cause certain of said needles to be in yarn-receiving relationship to the last mentioned of said yarn guides during

the movement of said reciprocable bed by the reciprocating means.

31. In a knitting machine, a needle bed, needles on said bed, a reciprocable bed, a plurality of yarn guides mounted on said reciprocable bed for movement into position in which the yarn may be received therefrom by at least certain of said needles, selective means for imparting such movement to said yarn guides, means to reciprocate said reciprocable bed while at least certain of said yarn guides are in said position so as to cause the same to feed yarn into position for needle reception, and means to selectively manipulate said needles to cause selected ones of the needles to be in yarn-receiving relationship to the last mentioned of said yarn guides during the movement of said reciprocable bed by said reciprocating means.
32. A knitting machine comprising a needle bed, needles on said bed, needle actuating means, said bed and said actuating means being mounted for relative movement, a yarn guide, a swingable member carrying said yarn-guide, means forming a unit with said bed in said relative movement for mounting said swingable member, and means forming a unit with said actuating means in said relative movement for imparting swinging movements to said swingable member first in one direction and then in the other.
33. Knitting mechanism comprising a needle bed, a series of needles thereon, a yarn-guiding element having yarn-guiding means and movable toward and away from a position wherein said yarn-guiding means is in proximity to said needles, a rocker element associated with said yarn-guiding means and adapted to be rocked by a control means, means to selectively control the disposition of said rocker element, and means operable on said rocker element to move said yarn-guiding means when said rocker element is disposed in one manner but not when it is disposed in another manner.
34. A yarn-guiding element comprising a yarn-guiding portion, a body portion, and a rocker pivotally mounted on said body portion and adapted to be selected by a selecting means for the control of the operation of the yarn-guiding portion.
35. In a circular knitting machine, in combination, a needle bed, a series of needles on said bed, a yarn guide, means to move said yarn guide past said needles in two directions, means to alter the general position of said yarn guide circumferentially of said bed, and means to cause needle-reception of yarn during the movement of said yarn guide in each direction.
36. In a circular knitting machine, in combination, a needle bed, a series of needles on said bed, yarn-guiding means, means to reciprocate said yarn-guiding means, said yarn-guiding means and said reciprocating means being so arranged that yarn may be fed to said needles pursuant to the movements of said yarn-guiding means in both directions, selectively operating means adapted to shift the general position of such yarn-guiding means circumferentially of said bed to cause the reciprocation thereof to occur relative to one portion of said bed at one time and relative to a different portion of said bed at another time, and selectively operative needle-operating means.
37. In a circular knitting machine, in combination, a needle bed, a series of needles on said bed, yarn-guiding means, mounting means for said yarn-guiding means, means to reciprocate said mounting means, means to shift the

general circumferential position of said mounting means with respect to said bed, means to cause yarn to be received by needles in proximity to said yarn-guiding means during a forward portion and a return portion of a reciprocatory movement of said mounting means, and pattern controlled means for shifting said mounting means.

38. In a circular knitting machine, in combination, a needle bed, a series of needles on said bed, yarn-guiding means, mounting means for said yarn-guiding means, means to support said mounting means in a manner to permit said mounting means to be shifted about said machine to any of a variety of positions with respect to said bed or to remain in any of said positions for a desired period, means independent of said shifting means to cause said yarn-guiding means to draw out yarn into position to be received by a plurality of said needles, and pattern controlled means for shifting said mounting means.

39. In a circular knitting machine, in combination, a needle bed, a series of needles on said bed, a dial, yarn-guiding means mounted for radial sliding movement on said dial, means to support said dial in a manner to permit said dial to be shifted about said machine to any of a variety of positions with respect to said bed or to remain in any of said positions for a desired period, selective means to cause reception by a plurality of said needles of yarn guided by said yarn-guiding means, and pattern controlled means for shifting said dial in a step-by-step manner about said machine.

40. A knitting machine comprising a needle bed, needles on said bed, yarn feeding means, means to selectively manipulate said needles, and means including at least certain of said needles to control the operation of said yarn-feeding means to limit the number of needles past which yarn is fed.

41. A circular knitting machine comprising a needle bed, a series of needles on said bed, yarn-feeding means, means to selectively position said needles, and means operated by certain of said needles when in one position but not when in another position to control the number of needles past which yarn from said yarn-feeding means is fed in any one feeding operation.

42. A circular knitting machine comprising a needle bed, a series of needles on said bed, an exterior dial, needle-operating means, said bed and said dial on the one hand and said needle-operating means on the other hand, being mounted for relative rotation, a plurality of yarn guiding members each constructed and arranged to pay out yarn and movably mounted for radial sliding movement on said dial between a plurality of radial positions, means for selectively causing radial movement of said yarn guiding members, yarn guiding portions on individual yarn guiding members, and means to cause yarn from a yarn guiding portion to be received by certain of said needles when the yarn guiding portion is in one radial position but not when it is in another radial position.

43. A circular knitting machine comprising a rotatable member, a non-rotating member, one of said members comprising a needle bed and the other of said members comprising needle-manipulating means, means to cause rotative movement of the rotatable member, a series of needles on said bed, a yarn guide, means associated with said bed for mounting said yarn guide, said yarn guide being mounted for move-

- ment from a position at the rear of the needles through a course extending in front of a plurality of said needles in one direction and then to a position at the rear of the needles and being
5 thereafter movable from a position at the rear of the needles through a course extending in front of a plurality of said needles in the opposite direction and then to the rear of the needles, and means to so move said yarn guide.
- 10 44. A circular knitting machine comprising a rotatable member, a non-rotating member, one of said members comprising a needle bed and the other of said members comprising primary yarn-feeding means, means to cause rotative
15 movement of the rotatable member, a series of needles on said bed, an auxiliary yarn guide adapted for feeding yarn to a limited number of said needles, means associated with said bed for mounting said yarn guide, means adapted to move said yarn guide from a position at the rear of the needles through the course extending in front of a plurality of said needles in one direction and then to a position at the rear of the needles and adapted thereafter to move said yarn guide from a position at the rear of the needles through a course extending in front of a plurality of needles in the opposite direction 10 and then to the rear of the needles, and means to manipulate said needles for the reception and incorporation into a fabric of yarn from said yarn-feeding means and said auxiliary yarn guide. 15

VINCENT LOMBARDI.

CERTIFICATE OF CORRECTION.

Patent No. 2,231,673.

February 11, 1941.

VINCENT LOMBARDI.

It is hereby certified that error appears in the printed specification of the above numbered patent requiring correction as follows: Page 7, first column, line 63, for the word "one" read --ones--; page 9, second column, line 63, after "chain" second occurrence, insert the word --sprocket--; page 10, second column, line 13, for the patent number "2,130,765" read --2,130,769--; page 14, first column, line 59, claim 13, for "import" read --impart--; and that the said Letters Patent should be read with this correction therein that the same may conform to the record of the case in the Patent Office.

Signed and sealed this 1st day of April, A. D. 1941.

(Seal)

Henry Van Arsdale,
Acting Commissioner of Patents.
